INDEXING MECHANISM

Ralph E. Flanders and Lee Davis, Springfield, Vt.,
assignors to Jones & Lamson Machine Company, Springfield, Vt., a corporation of Vermont

Application October 16, 1945, Serial No. 622,558

8 Claims. (Cl. 51—216)

1

This invention relates to mechanism particularly intended for indexing a thread grinder work spindle in accordance with multiple thread starts on the work. In order to grind threads properly there must be coordinated axial and angular relative motions between the work and the grinding wheel, and where the work is provided with a plurality of threads, this relationship is different for the different threads.

This invention has for an object, therefore, to automatically change the angular position of the work with relation to a given axial position after each pass of the grinding wheel so that the wheel may act successively on the series of multiple threads corresponding to the number of thread starts. The work, for example, may be a hob.

To this end and in accordance with this invention, the relation between the work rotating mechanism and the work spindle, while fixed during each grinding pass, is changed by a predetermined angular increment corresponding to the angular spacing of the several threads, as determined, for example, at the thread starts, between successive grinding passes.

For the purpose of illustration, this invention is shown as applied to a thread grinding machine of the type shown in the Flanders Patent No. 2,187,227, for Grinding machines, granted January 16, 1940. In this patent there is illustrated a thread grinding machine in which when threaded work with multiple threads is being ground, indexing from one to a succeeding thread may be accomplished by hand as described on page 6, second column, line 33 et seq. of that patent.

For a more complete understanding of this invention, reference may be had to the accompanying drawings in which:

Figure 1 is a fragmentary front elevation of a thread grinding machine embodying the invention.

Figure 2 is a detail sectional view to a larger scale on line 2—2 of Figure 1.

Figures 3, 4 and 6 are detail sectional views to a larger scale on the correspondingly numbered section lines of Figure 2.

Figure 5 is a detail sectional view on line 5—5 of Figure 4.

Figures 7 and 8 are detail sectional views on lines 7—7 and 8—8, respectively, of Figure 3.

Figure 9 is a diagram of the electric circuits.

Referring first to Figure 1, at 1 is shown the grinding machine bed supporting a traversing carriage 2 which has journaled therein in line with the traverse a work-carrying spindle 3 having a standard spindle nose 4 to which the work

2

piece is attached as is well understood in the art.

Suitable means are provided, as shown more particularly in the Flanders Patent No. 2,187,227, for rotating the work spindle and also for moving the work carriage back and forth in timed relation to the rotation of the work spindle. Such traversing of the work carriage is produced by the rotation of a lead screw 5 connected through to the spindle driving means by a suitable train of gears such that a definite axial position of the carriage corresponds to a definite angular position of the work.

The grinding wheel is shown at 6 supported by a grinding wheel carriage which is movable transverse to the direction of motion of the carriage 2 to present and retract the wheel with relation to the work, and the wheel may be angularly adjusted to correspond to the lead of the threads as more fully described in the Flanders patent.

The present invention has for its purpose the changing of the angular relation of the work corresponding to any axial position thereof so as to present the several threads of the work successively into operative relation to the grinding wheel, and to do this automatically after each pass of the wheel over a thread face.

As shown in Figure 3, the work spindle 3 is driven by a gear 7 which is journaled on a sleeve 8 and which is connected to drive this sleeve 8 through a ring 14 keyed to the sleeve 8 and a split ring 13 which may be clamped thereto. The ring 14 is provided with a lug 16 (see Figure 8) against which the pin 15 of the gear 7 may strike and the ring 13 also has a pin 17 which may also be contacted by the lug 16.

The gear 7 may be driven in either direction, depending upon whether right or left hand threads are being ground, and the angular spacing between the pins 15 and 17 provides a lost motion in the drive which allows for backlash in the driving mechanism between the spindle and the carriage 2, and particularly between the lead screw 5 and its cooperating nut carried by the carriage 2. The sleeve 8 has at its left hand end, as shown in Figure 3, a bevel gear portion 13 which meshes with a pair of planetary pinions 19 journaled on pivots 20 carried by a spider 21. These pinions 19 also mesh with a gear 22 keyed to the spindle 3. Thus as the gear 7 is rotated

after the impingement of the pin 15 against either the lug 16 or the pin 17, the sleeve 8 is rotated and as long as the cage 21 is held against rotation, motion is transmitted through the planetary pinions 19 to the gear 22 and thus to the spindle. By turning the cage 21, however,

while the gear 7 is stationary, the spindle 3 may be turned so as to displace the spindle angularly from its previous relation to the drive gear 7 and by so turning the cage 21 through the necessary angular extent, the work is stepped around so that the grinding wheel on the next pass of the carriage grinds on a thread face angularly spaced from that previously ground and this may be made to correspond with the angular spacing of the thread starts of the work. In order to produce this angular motion of the spindle 3 with reference to its driving mechanism, means are provided for turning the cage the required amount, at the end of each grinding pass, at other times the cage being held stationary so that the grinding is effected accurately on the thread face initially presented thereto. To this end the cage is formed with a worm wheel portion 25 with which meshes a worm 26 on a shaft 27, and as shown best in Figure 2, this shaft 27 is connected through change gears 28 and 29 with a second shaft 30.

The shaft 30, as shown best in Figure 3, carries a worm wheel 31 and a spiral cam disk 32. Meshing with the worm wheel 31 is a worm 33 carried by a worm shaft 34. As shown best in Figure 6, the worm 33 is mounted on the shaft 34 with capability of axial motion, the worm portion being mounted on a splined quill portion 35 of the shaft 34 and is normally pressed to one limit of its axial motion as by a spring 36 seated in a central bore 37 in the shaft 34 and reacting between a slide 38 extending through a slot 39 in the shaft 34 and which engages over one end of the worm 33 and a cap 40 threaded onto the outer end of the worm shaft 34. This worm shaft 34 extends outwardly of a casing 41 where it has keyed thereto a pulley 42 connected as through a driving belt 44 with a motor 45. By rotation of this motor 45, it will be evident that the worm 33 will be driven and through the worm wheel 31, the shaft 30 will be driven, and this through its change gears will drive the worm shaft 27 thus to index the spindle 3 with reference to its drive mechanism.

The means for controlling the rotation of the motor 45 comprises a solenoid 50 (Figures 3 and 9) which is energized as the carriage 2 approaches the end of its stroke, as by the closing of a switch 51 through a carriage dog 52. The energization of the solenoid 50 pulls upwardly a plunger 55 which is connected to a latch dog 56 (see Figure 3) pivoted at 57. This pulls the latch dog away from the locking shoulder 58 of the spiral cam 32, thus unlocking the shaft 30 for rotation. The dog 56 also carries a switch actuating arm 60 which lifts a switch actuating element 61 against the pressure of a spring 62 and closes a switch 63. The closing of the switch 63, as shown in Figure 9, closes a circuit from the lines *a* and *b* through a relay coil 64 which closes a pair of switch arms 65 and 66. The closing of the switch arm 65 closes a holding circuit for the relay 64 so that the breaking of the switch at 63 thereafter is not effective to release the relay, and the closing of the switch 66 acts to energize the motor 45. The rotation of the motor then turns the shaft 30 through the worm 33 and the worm wheel 31, and turns the cage 21. This action continues until a cam 70 adjustably fixed to the spiral cam 32 engages and pushes outwardly a switch actuating element 71 which opens the switch 72 in the holding circuit of the relay 64 which deenergizes the relay coil 64 opening the switch arms 65 and 66 which stops the rotation of the motor 45. 75

Any continued rotation of the motor 45 after the rotation of the shaft 30 is positively stopped by the dog 56 contacting with the shoulder 58 is expended in moving the worm wheel 33 along the shaft 34 in opposition to the spring 36, this mechanism thus acting as a yielding take-up to prevent breakage of the parts when the motor overruns and to make sure that the motor will run a sufficient length of time to complete the indexing action.

Means are also provided by which the direction of indexing may be reversed, depending upon whether right or left hand threads are being ground. This mechanism is shown particularly in Figures 4 and 5. The drive shaft 75 which drives the gear 7 is connected thereto through a sliding gear 77 on the shaft 75 which meshes directly with the gear 7, or to it through an idler shaft 78 having two gears 79 and 80. The gear 80 meshes with the gear 7, and the gear 79 meshes with the gear 77 when the gear 77 is slid out of mesh with the gear 7 and into mesh with the gear 79. The sliding motion of the gear 77 is produced by the axial motion of a rack bar 81 with the rack teeth of which meshes a pinion 82 on a reversing rock shaft 83 provided with a handle 84 on the outside of the gear casing 85 (see Figure 1). When the handle extends upwardly, the machine is adjusted for right hand threads, and when it is rocked downwardly the rack bar 81 is moved to its other position adjusted for left hand threads, thus reversing the relative directions of motion of the spindle and traverse. Both are reversed together to reverse the traverse direction as described in the Flanders patent to which reference has already been made.

From the foregoing description of an embodiment of this invention it should be evident to those skilled in the art that various changes and modifications might be made without departing from the spirit or scope of this invention.

We claim:

1. In a machine of the class described, a reciprocating carriage, a work spindle journaled in said carriage in line with its direction of reciprocation, a bevel gear fixed to said spindle, a spider journaled on said spindle and meshing with said bevel gear, a sleeve journaled on said spindle, a gear carried by said sleeve and with which said planetary gear meshes, means for rotating said sleeve and thereby through said planetary gear said spindle when said spider is stationary, means for rotating said spider to thereby adjust said spindle angularly relative to said sleeve, and means for reciprocating said carriage in time with the rotation of said sleeve.

2. In a machine of the class described, a reciprocating carriage, a work spindle journaled in said carriage in line with its direction of reciprocation, a bevel gear fixed to said spindle, a spider journaled on said spindle, a planetary gear journaled on said spider and meshing with said bevel gear, a sleeve journaled on said spindle, a gear carried by said sleeve and with which said planetary gear meshes, means for rotating said sleeve and thereby through said planetary gear said spindle when said spider is stationary, means for rotating said spider to thereby adjust said spindle angularly relative to said sleeve, and means for reciprocating said carriage in time with the rotation of said sleeve, said spindle being rotatable in either direction and said sleeve having a lost motion connection with said rotating

means for taking up backlash in said reciprocating means.

3. In a machine of the class described, a rotary work spindle, a grinding wheel, means for rotating said spindle and for traversing said spindle lengthwise in predetermined relation, means for turning said spindle angularly relative to its traverse position from said predetermined relation at predetermined times, power means for actuating said turning means, means for positively stopping said turning means after a predetermined extent of angular motion, and a yielding take-up interposed between said power means and turning means for absorbing the effect of said power means after such positive stopping has been effected until the power means stops.

4. In a machine of the class described, a rotary work spindle, a grinding wheel, means for rotating said spindle and for traversing said spindle lengthwise in predetermined relation, means for turning said spindle angularly relative to its traverse position from said predetermined relation at predetermined times, power means for actuating said turning means, means for positively stopping said turning means after a predetermined extent of angular motion, a drive interposed between said power means and turning means including a driving worm and a driven worm wheel, means supporting said worm for axial motion, and a spring pressing said worm to a limit of motion in one direction, said spring permitting axial motion of said worm opposed thereby on continued operation of said power means after such positive stopping has been effected.

5. In a machine of the class described, a rotary work spindle, means for rotating said spindle, means for moving said spindle axially in predetermined relation to such rotation, means including a planetary transmission having a normally stationary part between said rotating and said moving means, said normally stationary part determining by its position said predetermined relation, a motor for turning said normally stationary part, means actuated by said spindle when it reaches a predetermined axial position for energizing said motor, and means actuated when said normally stationary part reaches a predetermined angular position to de-energize said motor and to stop its own rotation.

6. In a machine of the class described, a rotary work spindle, means for rotating said spindle, means for moving said spindle axially in predeter-

mined relation to such rotation, means including a planetary transmission having a normally stationary part between said rotating and said moving means, said normally stationary part determining by its position said predetermined relation a motor for turning said normally stationary part, means actuated by said spindle when it reaches a predetermined axial position for energizing said motor, means actuated automatically to de-energize said motor and to stop its own rotation when said part has been rotated through said predetermined angular distance, and a spring take-up between said motor and part permitting over-running of said motor after the stopping of said part.

7. In a machine of the class described, a rotary work spindle, means for rotating said spindle, means for moving said spindle axially in predetermined relation to said rotation, means including a planetary transmission between said rotating means and said moving means, said planetary transmission including a normally stationary part determining by its position said predetermined relation, and power means for automatically turning said normally stationary part at intervals to thereby change said predetermined relation.

8. In a machine of the class described, a rotary work spindle, means for rotating said spindle, means for moving said spindle axially in predetermined relation to said rotation, means including a planetary transmission between said rotating means and said moving means, said planetary transmission including a normally stationary part determining by its position said predetermined relation, and power means for automatically turning said normally stationary part when said spindle reaches a predetermined axial position to thereby change said predetermined relation.
